SUPPORTING UNIT FOR BARBECUES OR THE LIKE

Clarence M. Ellis, Lodi, Calif., assignor of one-third to J. E. Devine, Lodi, Calif., and one-third to Lilybelle Prentice, Acampo, Calif.

Application April 18, 1949, Serial No. 2,100

Term of patent 14 years

(Cl. D81—10)

To all whom it may concern:

Be it known that I, Clarence M. Ellis, a citizen of the United States, residing at Lodi, in the county of San Joaquin, State of California, have invented a new, original, and ornamental Design for a Supporting Unit for Barbecues or the like, of which the following is a specification, reference being had to the accompanying drawing, forming a part thereof.

The figure on the drawing is a perspective view of a supporting unit for barbecues or the like looking at one side thereof and showing my new design, the opposite side of the device presenting the same appearance.

The essential features of my design reside in the portions shown in full lines.

I claim:

The ornamental design for a supporting unit for barbecues, or the like, as shown and described.

CLARENCE M. ELLIS.
